Charles B. Tuttle of Amherst, N.H.
Letters Patent No. 506 Dated October 5th 1852.

The schedule referred to in these Letters Patent and making part of the same
To all persons to whom these presents shall come:

Be it known that I, Charles B. Tuttle, of Amherst, in the County of Hillsborough, and State of New Hampshire, have invented or produced a new ornamental design for a Cooking Stove, and do hereby declare that the same is represented in the accompanying drawings.

Of the said drawings Figure 1 denotes the ornamental configuration of the vertical side plate of the Stove. Figure 2. is a view of the rear plate of the same. Figure 3. is a view of the front plate of it. Figure 4 is a vertical section of the front plate taken through one of the fire place doors. Figure 5 is a vertical section of the rear plate taken through the middle of it. Figure 6 is a vertical section of the side plate taken through the middle of its larger door.

The ornamental configuration of mouldings, panels, and central figures of the panels and doors, together with the figures of each of the feet of the Stove as exhibited in the drawings is believed to be novel. A person skilled in the art of Design as applied to forming patterns for stone plates will readily discover

Des. 506

from the drawings not only the peculiarities of form of the various parts constituting the design, but the nature and purpose of each represented portion of such drawings, whether it be a door, panel or otherwise.

What I claim as my invention or production is the ornamental design for a Cooking Stove substantially as represented in the accompanying drawings.

In testimony whereof I have hereunto set my
signature this twenty second day of June A.D. 1852
